(57) **CLAIM**

The ornamental design for an adjustable buckle, as shown and described.

DESCRIPTION

FIG. 1 is a first perspective view of the first embodiment of an adjustable buckle showing my new design; FIG. 2 is a second perspective view of the first embodiment thereof;

FIG. 3 is a front view of the first embodiment thereof;

FIG. 4 is a back view of the first embodiment thereof;

FIG. 5 is a left side view of the first embodiment thereof;

FIG. 6 is a right side view of the first embodiment thereof;

FIG. 7 is a top view of the first embodiment thereof;

FIG. 8 is a bottom view of the first embodiment thereof;

FIG. 9 is a first perspective view of the second embodiment of an adjustable buckle showing my new design;

FIG. 10 is a second perspective view of the second embodiment thereof;

FIG. 11 is a front view of the second embodiment thereof;

FIG. 12 is a back view of the second embodiment thereof;

FIG. 13 is a left side view of the second embodiment thereof;

FIG. 14 is a right side view of the second embodiment thereof;

FIG. 15 is a top view of the second embodiment thereof;

FIG. 16 is a bottom view of the second embodiment thereof; and,

FIG. 17 is an enlarged view of the selected portion 17 in FIG. 1.

The broken lines shown in the drawings depict portions of the adjustable buckle that form no part of the claimed design.

1 Claim, 17 Drawing Sheets
